UNITED STATES PATENT OFFICE.

JOHN WALTER, OF NASHVILLE, TENNESSEE.

CAR-ROOF.

SPECIFICATION forming part of Letters Patent No. 286,877, dated October 16, 1883.

Application filed July 27, 1883. (No model.)

To all whom it may concern:

Be it known that I, JOHN WALTER, of Nashville, in the county of Davidson and State of Tennessee, have invented a new and useful Improvement in Car-Roofs; and I do hereby declare that the following is a full, clear, and exact description of the same, reference being had to the accompanying drawings, forming part of this specification, in which—

10 Figure 1 is a partial plan view of a car-roof with one of the plates removed and a portion of the hand-rail and running-board broken away. Fig. 2 is a cross-section through the line *a a* of Fig. 1, and Fig. 3 is an edge view 15 of the roof from the side of the car.

My invention relates to roofs for railway-cars; and its object is to provide a readily detachable or portable roof which may be quickly removed or applied in part or whole, and 20 also to afford greater security to the brakeman in running along the top of the car, as well as to provide an efficient means for ventilating the car. These objects are attained in the construction and arrangement of parts which 25 I will now proceed to describe.

In the drawings, *A* represents the sheathing or top casing of the car-body, which forms the foundation for the roof, and has a slight inclination or slope upon each side from the 30 middle line of the car. The roof is composed of sheet-metal plates *B* and *B'*, arranged alternately and extending from the apex of the car-roof to the sides thereof. The two plates *B* and *B'* are of different construction, and are 35 adapted, when placed together, to form a watertight joint. The two edges of any one plate are exactly alike. The plates *B* are screwed or nailed to the sheathing a distance apart equal to the width of plates *B'*, and the latter 40 are then slid longitudinally upon and over the edges of the plates *B*, to form the necessary connection and a tight joint. The plates *B* have their longitudinal edges bent (see Fig. 3) first upwardly and inwardly toward the plate, 45 to form the ledge or flange *a*, then back upon the flange and downwardly, and then up to form the groove or trough *b*, and then down again and horizontally at *g*. The plates *B'* have their longitudinal edges bent upwardly

and outwardly from the plate at an obtuse 50 angle at *c*, then horizontally at *d*, and then downwardly and inwardly toward the plate at *e*. In fitting the plates, those marked *B* are screwed or nailed to the sheathing by screws or nails passing through the horizontal edges 55 *g*, and the plates *B'* are then slid longitudinally over the edges of plates *B*, the edge *e* fitting over flange *a*, and the horizontal bend *c* covering the trough or groove *b*. The plates *B* being attached to the sheathing by screws which 60 are covered by plates *B'*, no water can pass through the screw-holes, and as the side seams or joints have a housed drain-trough, *b*, with corrugations on each side, no water can work in at this joint, and if any does get in it passes 65 out the drain-trough *b*.

At the upper ends of the plates *B'* the upturned flanges *h* are disconnected on opposite sides of the middle of the car, so that said plates may be drawn apart from each other in taking 70 the roof off the car; but the upper flanges, *i*, of the plates *B* are turned over each other to form a connection or tie across the apex of the roof. At the lower edges of both series of plates are downwardly-projecting flanges *j* and 75 *k*, which are nailed or screwed to the barge-boards or sides of the car.

Extending along the middle line of the car is the running-board *C*, which has supports *l* on each side of the middle, which rest upon 80 the flat part of the roof-plates. In the middle of this running-board, on the under side, is a ventilating groove, *m*, which communicates with holes in the top of the car through the spaces between the disconnected flanges *h* of 85 the plates *B'*, thus securing the ventilation of the car.

In sleety weather, or when the car-roof is covered with ice, the passing of the brakeman over the top of the car is attended with great 90 danger of slipping off. To prevent this I provide a hand-rail, *E*, which extends alongside of the running-board, and is sustained in brackets *F* five or six inches above the roof of the car. These brackets are screwed or riveted 95 to the sliding plates *B'*, an elastic packing being interposed between them and the plate to close the hole against leakage. These brack-

ets are also bolted horizontally through the running-board, as shown at m^2 . The hand-rail is contained in sleeves or sockets of the brackets, and may be removed therefrom, when 5 the plates are to be taken off, by slipping said rail endwise through said sleeves. For forming this hand-rail, sections of gas-pipe are well adapted, and the ends may be joined to form a union of the sections by a screw-coupling at 10 the sleeves of the brackets.

Having thus described my invention, what I claim as new is—

1. A roof composed of plates B and B', arranged alternately, the plate B being formed 15 with longitudinal flange *a* and groove *b* at each of its edges and screwed to the sheathing, and the plate B' having overlapping bend *c d* and hooked edge *e*, adapted to slide upon the edge 20 of other plate and cover it, substantially as described.

2. The combination, with a car-roof formed of alternate plates B and B', and having openings at the apex, of the running-board C, having supports *l*, resting upon the flat faces of the plates, as and for the purpose described. 25

3. The combination, with the sliding plates B', carrying brackets, of a hand-rail mounted upon said brackets, as and for the purpose described.

4. The combination of the sliding plates B', carrying brackets, and a hand-rail sustained 30 therein, the running-board, and means for securing the running-board to the brackets, as and for the purpose described.

JOHN WALTER.
